ROLLER PRESS FOR THE BRIQUETTING OF ORE, COAL OR SIMILAR MATERIAL

Johannes Bernhard Decker, Kolin-Rath, Germany, assignor to Klockner-Humboldt-Deutz Aktiengesellschaft, Kolin-Deutz, Germany, a corporation of Germany

Filed Feb. 20, 1957, Ser. No. 641,369

Claims priority, application Germany Feb. 23, 1956

15 Claims. (Cl. 25—77)

In the known roller-type briquetting presses, the material to be briquetted is supplied in loose, comminuted condition directly between the rollers of the press. The briquettes made in this manner have relatively slight strength so that great friction losses occur during further handling. To increase the strength of the briquettes, it has been proposed to again comminute the briquettes after their first passage through the press and to then repeat the briquetting operation. The first passage through the press then results in some pre-compacting of the material, and the second passage serves for obtaining the desired shape of the briquettes. It is possible in this manner to produce briquettes of great strength, but the considerable work required for the repeated briquetting and the intermediate comminuting operations constitute a notable disadvantage.

It is an object of the invention to avoid such disadvantages and to accomplish, in a simple manner, an effective de-aeration and pre-compression of the briquetting material and to supply this material to the press so as to secure the production of briquettes of great strength in a single pressing operation.

To this end, and in accordance with a feature of my invention, I provide a roller-type briquetting press with an opposed pair of rollers rotating in opposite directions about their respective axes and with a distributor box for the material to be briquetted. The box is mounted above the rollers and its bottom has an opening, or openings, substantially centered above and between each pair of rollers. The distributor box is provided with an oscillating mounting and is connected to an oscillation generator which imparts to the box mainly vertical oscillations of relatively high frequency. These features have a further advantage in that they permit the increasing of the operating speed of the rollers, and thus the output of the briquetting press.

The foregoing and other more specific objects, advantages and features will be apparent from the preferred embodiment of the invention shown in the accompanying drawings and described hereinafter. In the drawings:

Fig. 1 is a side view of the roller-type briquetting press;

Fig. 2 is a cross section along the line II—II in Fig. 1;

Fig. 3 is a cross section along the line III—III in Fig. 1;

Fig. 4 shows a detail of the distributor box of Fig. 1 on enlarged scale.

Fig. 5 is a cross section along line V—V in Fig. 4;

Fig. 6 shows a detail of Fig. 5 along the section line VI—VI.

Fig. 7 shows a detail, partially in section, of the vibrator and its mounting.

The fundamental design of the roller-type briquetting press is apparent from Figs. 1 to 3. A machine frame, consisting essentially of two lateral walls 1 and 2, is mounted on a foundation 3, being connected therewith by means of anchor bolts (not illustrated). Each of the two side walls 1 and 2, as shown in Fig. 2, has the shape of an H in profile and is provided with re-enforcing webs.

2

4 and 5. Mounted on the flange portions 6 and 7 of the side walls are respective bearings 8, 9 and 10 for three shafts 11, 12 and 13. The bearings are designed as slide bearings, for adjustment purposes, and each comprises a rectangular block with inserted or inner shells or rings 14 and 15' (Fig. 2) of bearing metal. The cylindrical shafts have respective portions of different diameters so that they cannot become displaced in the axial direction. A spur gear 15 (Fig. 3) and a roller 17 are mounted on shaft 11 between its two bearings 8. The shaft 12 (Fig. 2) carries a spur gear 16 and a roller 18 between two bearings 9. Each roller is formed of a strong wheel body and a ring 63 of material resistive to abrasive wear, the ring 63 being shrunk onto the wheel body. As shown in Figs. 1 and 3 the ring 63 is provided with the usual mold forming depressions at 630. The depressions on the two rollers jointly form the briquette. The two spur gears 15 and 16 mesh with each other as apparent from Fig. 3. Mounted on shaft 13 is a pinion gear 19 meshing with the gear 16. Mounted on one of the outer ends of shaft 13 is a clutch 20 for connecting the shaft with a drive gear and a drive motor (not illustrated).

The rectangular bearing blocks 8, 9 and 10 are kept at a different spacing from one another by means of spacer structures 21 to 25. These spacer structures as well as the shafts 11, 12 and 13 are covered from above by means of head pieces 26 and 27 (Fig. 3). The two outermost spacer structures 21 and 25 are secured from displacement in the longitudinal direction by means of wedges 28 and 29. The spacer structures are further connected with the side walls 1 and 2 on one hand and with the head pieces 26 and 27 on the other hand by means of screws which are represented in Fig. 1 by broken line 30. In order to compensate for wear at the surface of the rollers, several spacer plates 31 are inserted between the bearing 8 and the spacer structure 23 as may be desirable during the operation of the machine from time to time. The same number of spacer sheets 31 are provided at each of the two side walls. As shown, simplified, in Fig. 1, a wedge 32 is provided to tension the bearings as well as the spacer structures in the longitudinal direction. This tensioning device may also be so designated that it acts as a safety shearing member to protect the machine from damage due to occurrence of excessively large forces, for instance in the event that a metallic body enters between the rollers.

Fastened upon the head pieces 26 and 27 are standards 33 and 34 which carry a distributor box 35. The distributor box has a feed opening 36 on its top for the supply of the material to be briquetted. The box is further connected with a driving means 37, comprising an electric gear-type motor. The drive is connected with a vertical shaft 38 whose lower end carries a double armed stirrer 39. The stirrer is located closely above the bottom 40 of the distributor box. As shown in Figs. 4 to 6, the bottom 40 of the distributor box is a flat plate of circular shape which is reinforced on its lower side by webs 41, and by means of a peripheral rim portion or flange 42. The lower side of the rim portion 42 is joined to the planar plate 40 and widens upwardly, providing a conical flange surrounding the lower end of the distributor box 35. A preferably rectangular opening 43 is provided in bottom 40. A short conduit 44 extends downwardly from the opening 43 and opens into a chute 45 (Fig. 2). The width of the chute corresponds to or is slightly greater than the width of the appertaining rollers so that a uniform distribution of the material in the axial direction of the rollers is obtained. Secured on the outer periphery of the rim portion 42 are vertical plates 46. Similar plates 47 are fastened to the lower end of the distributor box 35. The exterior ends of plates 46 and 47 lie opposite each other and an

elastic body 48 of rubber is disposed between them and secured in position by bolts and nuts 49, 50. The bolts are secured in the rubber. There is no metallic connection between plates 46 and 47. The rubber "springs" 48, as apparent from Fig. 6, are circular in cross section. However, a substantially rectangular cross section of the rubber springs is also of advantage in some cases.

Mounted on the lower side of bottom plate 40 and in the center thereof is an electromagnetic vibrator 51. This vibrator is designed as follows. Located within a housing, firmly joined with the bottom 40, is a movable magnetic member. This member is held on both sides by two respective springs (not shown) and thus is capable of oscillation, the axes of the two respective springs being coincident with the preferred direction of oscillation. Mounted on the magnetic part are two magnet cores which are surrounded by two respective magnet coils. The magnet cores are located as closely as possible to an armature which is connected with the housing of the vibrator, but the cores are sufficiently spaced from the housing so that an oscillating movement of the magnetic part is not impeded. If alternating current, for instance 50 cycles per second, is supplied to the magnet coils by means of electric supply leads (not illustrated), then the magnet cores and thus the magnetic part are alternately attracted to the armature, thus producing an oscillating motion of 6000 oscillations per minute. In certain cases, however, it is also advantageous to operate the vibrator with a lower oscillation frequency, for instance at 3000 oscillations per minute. For this purpose, a simple rectifier may be connected ahead of the vibrator so that the electric current can flow in only one direction through the vibrator with the result that the vibrating frequency is reduced to half of the alternating-current value. The control of the electromagnetic vibrator is effected by an additional control device, such as a rheostat controlling the current (not illustrated). This device permits a stepless regulation of the oscillating amplitude, namely from 0 mm. to about 2 mm. Additional weights may be mounted on the magnet part in order to increase the mass of the oscillating system and hence also the amplitude. The frequency of the vibrator can also be reduced stepwise by changing the current frequency.

The opening 43 in the bottom of the distributor box can be closed partly or entirely by means of a slider 52 (Fig. 1) operable from the side of the machine, so that, if desired, little or no material will drop into the chute 45. The chute 45 has a rectangular cross section. Its two side walls 53 and 54 have their lower ends so designed that they straddle the two rollers 17 and 18 laterally and protrude downwardly a sufficient extent to laterally seal the wedge-shape space 55 in the center above the two rollers 17 and 18. The wall 56 of chute 45 is stationary and terminates closely above the roller 18. The opposite wall 57, however, is pivoted at 58 near its upper end and can be shifted or tilted in controlled degree toward the roller 18, by means of a rod 59 and a hand wheel 60. The rod 59 is pivotally linked with the wall 57 and is supported on its other end by a holder 61.

The operation of the above-described machine is as follows. The material to be briquetted, which if desired may be mixed with a suitable binding substance and may be preheated by means of steam, is fed into the distributor box 35 through the opening 36. The electromagnet vibrator, which is capable of producing accelerations up to about six times gravity acceleration (6 g) imparts predominantly vertical oscillations to the bottom of the distributor box. In this manner the material within the distributor box is strongly shaken, de- aerated, and is pre-densified to a very large extent. The briquetting material thus pre-compacted is introduced by means of the double arm 39 through the opening 43 into the chute 45. In this manner, the material enters

or passes between the two rollers 17, 18 and is pressed into briquettes of oval shape, for example. The pressed briquettes drop out of the briquetting press through the opening 62 in foundation 3. Beneath the foundation, 5 the finished briquettes can be separated from slight unavoidable amounts of non-briquetted material, the separation being effected by means of a screening device of conventional type. The briquettes can be conveyed by means of a conveyor belt away from the screening device, whereas the non-briquetted material is returned into the distributor box of the briquetting press. The pre- compacting can be modified by varying the oscillation frequency of the electromagnetic vibrator in accordance with any desired requirements. Generally, the oscillation frequency is about 3000 oscillations per minute 15 and the amplitude stroke of the bottom plate 40 is between about 0.5 mm. and about 1.3 mm. However, the pre-compacting can be further increased by adjusting the wall 57 toward the roller 18 as far as possible, so that the briquetting material does not drop freely through the shaft 45 but is subjected in the shaft to an additional amount of compacting, because it is subjected to the pressure of the material located above.

The rubber springs 48 serve a double purpose. They 25 operate as springs for the oscillatory motion of the bottom 40 relative to the distributor box 35; the resulting stresses in the rubber bodies being shearing stresses. The rubber springs also serve to receive and convey the forces which are produced by the rotating movement of the 30 double arm 39 and which attempt to entrain or carry along the bottom 40. For the latter purpose, the vertical plates 46 and 47 are preferably so arranged that these forces press the rubber springs in compression. If desired, five or more rubber springs may be distributed 35 over the periphery instead of the four rubber springs illustrated. In certain cases, however, three such springs are sufficient.

While in the illustrated embodiment, the wall 57 of chute 45 is displaceable, a different wall of the chute, 40 or two of its walls, can be pivotally mounted in an analogous manner. Furthermore, while in the illustrated embodiment only the bottom of the distributor box is oscillatingly mounted, the entire distributor box can be oscillated, the oscillations being mainly vertically directed. In the latter modification, the bottom is connected with the other parts of the distributor box and the entire box structure is vibratory mounted, by means of springs, relative to the stationary machine frame.

In the above-described embodiments, the vibration 50 generator is of the electromagnetic type. Instead of an electromagnetic vibrator, other types of oscillation generators, such as for instance purely mechanical oscillators, are applicable. Of advantage for instance is a known 55 oscillation generator which operates with two unbalanced weights that rotate in mutually opposed directions. The two unbalanced weights are mounted on two shafts driven in respectively opposing directions. The shafts are journaled on the vibratory mounted machine portion so that the horizontal force components of the unbalanced 60 forces in the horizontal direction counteract and compensate each other, whereas the vertical components of the unbalance forces are fully effective and produce vertical oscillations of the machine portion. This makes it possible in a simple manner to vary the frequency of oscillations to any desired amount, for instance so that the machine can operate between about 1000 or 65 1500 oscillations per minute.

In some cases it is of further advantage to substitute 70 for the double arm 39 a different mechanical device situated in the distributor box or in the shaft 45, which device presses the briquetting material downwardly, but toward and between the rollers.

The invention is analogously applicable to roller-type 75 briquetting presses equipped with more than two rollers, and to presses the rollers of which are provided with

three, or more or less, peripheral rows of molds. Each set of rollers can be equipped with an individual box 35 and oscillator 51, or a single box and oscillator can feed all of the sets.

As mentioned above, the briquetting material, prior to charging it into the distributor box, may be mixed with a binding agent, such as pitch or tar. Another advantage of the invention is the fact that, by virtue of the pre-compacting, the quantity of the binding agent can be considerably reduced.

It will be obvious to those skilled in the art, upon a study of this disclosure, that our invention permits of various modifications with respect to design and arrangement of the machine components, and hence may be embodied in machines other than the one particularly illustrated and described herein, without departing from the essential features of our invention, and within the scope of the claims annexed hereto.

As shown in Fig. 7 the above described vibrator 51 comprises a housing 64 in which a movable magnetic member 65 is mounted between two pairs of springs 66. This member 65 carries two magnet coils 67 with appertaining current supply springs 68, as well as two magnet cores 72 which terminate with slight clearance in front of an iron armature 69 so as to form an air gap 70 together therewith. When energizing the vibrator by alternating current, the magnetic member 65 is placed into vertical oscillations. These are transmitted through the springs 66 to the housing 64 and plate 71 and thence to the above detailed bottom plate 40.

I claim:

1. In a press for briquetting ore, coal, and similar materials, pressing means comprising two press rollers, briquette-forming depressions on said pressing means, the rollers turning about their axes in opposite directions, the roller surfaces moving downwardly in the region where they come together, a distributor box to distribute material to be briquetted between the rollers above the place where they come together, the distributor box having an upper part and also having a bottom plate on which the material is supported, the bottom plate being vibratable to and from the upper part, means to vibrate said plate upwardly and downwardly, the distributor box having an outlet for the material leading to said region, a rotary stirrer above the plate, effective to force the material to the outlet, the upper part of the box having a number of substantially vertical fastening plates attached thereto, substantially vertical fastening plates carrying the bottom plate, resilient compressible means between and connecting respective fastening plates of the upper part with respective fastening plates of the bottom plate, whereby the bottom plate is resiliently suspended from the upper part.

2. The apparatus defined in claim 1 in which the resilient means comprise rubber bodies.

3. In a press for briquetting ore, coal, and similar materials, pressing means comprising two press rollers, briquette-forming depressions on said pressing means, the rollers turning about their axes in opposite directions, the roller surfaces moving downwardly where they come together, distributor means mounted above the rollers to distribute material to be briquetted between the rollers above the place where they come together, the distributor means comprising a plate on which the material is supported, said plate being resiliently supported for oscillation and being provided with an opening and conduit means directed towards said place where the rollers come together for passing said material thereto, stirring means mounted above said plate for driving said material to said opening, and means to vibrate said plate in a direction substantially upward and downward only and with a force and acceleration such as to effect a pre-compression and de-aeration of the material, said means to vibrate being suspended from the center of the underside of the plate.

4. In a press for briquetting ore, coal, and similar materials, pressing means comprising two press rollers, briquette-forming depressions on said pressing means, the rollers turning about their axes in opposite directions, the roller surfaces moving downwardly where they come together, a distributor box to distribute material to be briquetted between the rollers above the region where they come together, the distributor box having an upper stationary part and also having a bottom plate structure 10 on which the material is supported, the bottom plate structure being resiliently mounted for vertical oscillation relative to the upper part, means to vibrate said plate structure essentially upwardly and downwardly for pre-compacting said material, the bottom plate structure 15 comprising a bottom plate and a rim flange carried thereon, the flange extending upwardly and overlapping the lower part of the box, means forming an opening in said bottom plate and disposed above said region for feeding the initially compressed material from said plate 20 into said region, and stirring means mounted above said plate for driving said material to said opening.

5. In a press for briquetting ore, coal, and similar materials, pressing means comprising two press rollers, briquette-forming depressions on said pressing means, the rollers turning about their axes in opposite directions, the roller surfaces moving downwardly where they come together, a distributor box to distribute material to be briquetted between the rollers above the region where they come together, the distributor box having an upper 25 part and also having a bottom plate on which the material is received, the bottom plate being resiliently mounted for vertical oscillation relative to said upper part, means to vibrate said plate upwardly and downwardly, the bottom plate having an exit opening for the 30 material, stirring means mounted above said plate for moving said material to said opening, a stationary vertical chute of rectangular cross section communicating with the opening and extending downward toward the rollers, the chute having two opposite walls projecting 35 downwardly in close proximity to the sides of the rollers, one of the other two walls being pivoted, and means to swing the lower part of said one wall toward the other and to adjust it in position.

6. In a press for briquetting ore, coal, and similar materials, pressing means comprising two press rollers, 45 briquette-forming depressions on said pressing means, the rollers turning about their axes in opposite directions, the roller surfaces moving downwardly in the region where they come together, a distributor box to distribute material to be briquetted between the rollers above said 50 region where they come together, the distributor box having an upper part and also having a bottom plate on which the material is supported, the bottom plate being vibratable to and from the upper part, means to vibrate said plate upwardly and downwardly, the distributor box 55 having an outlet for the material leading to said region, a rotary stirrer above the plate, effective to force the material to the outlet, the upper part of the box having a number of substantially vertical fastening plates attached thereto, substantially vertical fastening plates carrying the bottom plate, resilient compressible means between and connecting respective fastening plates of the upper part with respective fastening plates of the bottom plate, whereby the bottom plate is resiliently suspended 60 from the upper part, the means to vibrate said bottom plate being an electromagnetic vibrator suspended from the underside of the plate, the vibrator having an amplitude of oscillation of not more than about 1.3 mm.

7. The apparatus defined in claim 1, the means to vibrate the device having a rating sufficient to oscillate the device at least about 1000 oscillations per minute, with an amplitude of about 0.5 mm. to about 1.3 mm.

8. In a press for briquetting ore, coal, and similar materials, pressing means comprising two press rollers, briquette-forming depressions on said pressing means, the

roller surfaces turning about their axes in opposite directions, the rollers moving downwardly where they come together, a distributor box to distribute material to be briquetted between the rollers above the region where they come together, the distributor box having an upper part and also having a bottom plate on which the material is supported, the bottom plate being resiliently mounted for vertical oscillation to and from the upper part, said plate being provided with an opening and conduit means directed towards said region to carry the material thereto, stirring means mounted above said plate for driving said material to said opening, and means to vibrate said plate upwardly and downwardly with a force and acceleration sufficient to de-aerate and compact said material, the means to vibrate the bottom plate being an electromagnetic vibrator suspended from the underside of the plate and having a rating sufficient to vibrate the plate at least about 1000 oscillations per minute, with an amplitude of about 0.5 mm. to about 1.3 mm.

9. In a press for briquetting ore, coal, and similar materials, pressing means comprising two press rollers, briquette-forming depressions on said pressing means, the rollers turning about their axes in opposite directions, the roller surfaces moving downwardly where they come together, a distributor box to distribute material to be briquetted between the rollers above the region where they come together, the distributor box having an upper part and also having a bottom plate on which the material is supported, the bottom plate being resiliently mounted for oscillation vibratable to and from the upper part, said plate being provided with an opening and conduit means directed towards said region to carry the material thereto, stirring means mounted above said plate for driving said material to said opening, and means to vibrate said plate upwardly and downwardly, the upper part of the box having a number of substantially vertical fastening plates attached thereto, substantially vertical fastening plates carrying the bottom plate, resilient compressible means between and connecting respective fastening plates of the upper part with respective fastening plates of the bottom plate.

10. The apparatus defined in claim 9 in which the resilient compressible means are rubber bodies.

11. In a roller briquetting press for briquetting of ore, coal, and similar materials, and equipped with a pair of rollers provided with briquette-forming depressions, said rollers being rotatable in mutually opposite directions, the combination with said rollers of distributing container means having a feeding mechanism for delivering the material to be briquetted to said rollers, said distributing container means being mounted above said rollers and having an upper portion and a horizontal bottom plate, resilient mounting means elastically joining said bottom plate to said upper portion for relative motion of said plate in a vertical direction, said plate being provided with an opening located above said rollers for supplying the material thereto disposed above said rollers, said feeding mechanism comprising a device mounted above said bottom plate for driving the material to said opening, an oscillation generator connected with said distributing container means for exciting said bottom plate to oscillate at a frequency in excess of about 1000 oscillations per minute essentially in a vertical direction at a force and acceleration sufficient for de-airing and pre-

densifying said material in bulk form before said material is supplied to said rollers, and means for attaching said oscillation generator to said bottom plate for uniformly distributing said oscillations over the entire surface

5 of said bottom plate.

12. In a roller briquetting press according to claim 11, said opening in said bottom plate being located above the middle region where said rollers come together, said resilient mounting means comprising a resilient connection between said bottom plate and said distributing container means, said oscillation generator being fixedly connected with said bottom plate, said bottom plate comprising a planar plate having a rim widening conically in the upward direction, the lower end of said rim surrounding the fixed portion of said distributing container means.

13. In a roller briquetting press according to claim 12, said upper portion of said distributing container means being fixedly mounted to said press, a first metal plate

20 fastened to said bottom plate of said feeding mechanism, a second metal plate fastened to said fixed portion of said distributing container means, said resilient mounting means comprising at least three rubber buffers uniformly distributed around the periphery of said bottom and connected between said first and second metal plates for oscillatingly mounting said bottom of said feeding mechanism to the balance of said distributing container means.

14. In a briquetting press according to claim 11, said oscillation generator being centrally located beneath the bottom of said distributing container means, and comprising an electromagnetic vibrator.

15. In a roller briquetting press according to claim 11, a vertical chute disposed beneath said opening in said bottom plate for passing said material to the space between said rollers, said chute having a rectangular cross section, one wall of said chute being pivotally mounted at its upper end, and control means linked to said one wall for tilting said one wall about its pivot in relation to the other walls of said chute for adjusting the rate of travel of the material through said chute and thus adjusting the degree of pre-compaction thereof in said feeding mechanism.
